UNITED STATES PATENT OFFICE.

WILLIAM OLDFIELD, OF NEW BEDFORD, MASSACHUSETTS.

BREAK-DETECTOR AND WARP-SEPARATOR FOR LOOMS.

1,123,137.

Specification of Letters Patent. Patented Dec. 29, 1914.

Application filed July 22, 1913. Serial No. 780,542.

To all whom it may concern:

Be it known that I, WILLIAM OLDFIELD, a citizen of the United States, residing at New Bedford, in the county of Bristol and State of Massachusetts, have invented new and useful Improvements in Break-Detectors and Warp-Separators for Looms, of which the following is a full, clear, and exact description.

10 This invention relates to means for locating the break of a warp thread in weaving, and in carrying the invention into practice, the frame or other appropriate part of the loom maintains supports for one or more manually movable and appropriately notched bars with which drops that are suspended by the warp threads may engage when a warp thread breaks or becomes slack, so that the drop may be moved by the bar 15 to engage with an adjacent drop and provide a space, thereby not only locating the break, but also providing a space of such size that the drop may be reached, re-threaded and the broken warp joined.

25 My invention is not directed toward providing a stop motion which is automatically effective when a warp thread breaks, but is directed toward providing means for readily and practically indicating the location of a 30 broken warp thread, and then separating by manual actuation the warp at the place where the break occurs, the separation of the warps providing ample space for picking up the drop, threading the same and joining the 35 warp.

In practice, my invention is applied to a loom between the heddles and the warp beam.

40 In the accompanying drawings which illustrate the preferred form of my invention that is designated by me as "A break detector and warp separator for looms."

Figure 1 is a view in outline illustrating a portion of the loom, and showing the position of the drops and notched bars, the bars being shown in section; Fig. 2 is a plan view showing the side frames of the loom, the supporting brackets for the notched bars, the notched bars and drops, the bars extending diagonally to the frame; Fig. 3 is a detail view showing a notched bar and a supporting bracket; Fig. 4 is a front view of a portion of the sliding bar showing the drops thereon; Fig. 5 is a view of one of the 55 brackets which maintains the sliding bar;

Figs. 6 and 7 are detail views of one of the brackets or bar supports; Fig. 8 is a plan view of the clip; Fig. 9 is a view of the pin; and Figs. 10 and 11 are transverse sectional views of the bars, Fig. 10 being a preferred form and Fig. 11 a modification.

Referring to the drawings 1 is the side frame of the loom, 2 the warp beam, 3 the roller, 4, 4, the rods, 5, 5, the heddles, 6, 6, the warp, 7 the lay, and 8 the breast beam, such parts being of ordinary construction.

The side frame of the loom has attached thereto in any suitable manner, either by clips or bolts and washers, bar supports or brackets 9, 9', which are located preferably at a point below the plane of the roller 3 and the rods 4, a convenient point of attachment being above the warp beam.

The brackets 9 and 9' have slots 10 in their upper portions and the intermediate part 11 of the bracket 9 between the slots and on their outer faces have attached thereto blocks 12, the blocks having therethrough horizontal openings for pins 13, of sufficient length to extend beyond the adjacent walls 75 of the slots 10. The blocks attached to the brackets are also provided with vertical openings to receive lock pins 14 that enter 80 openings in the pins 13 and hold the same against lateral movement.

The lock pins project slightly so that they may be taken out when it is desired to remove or slide to one side one of the pins 13 to take out one or both of the notched bars 15. The notched sliding rods or bars 15 are of a length sufficient to extend beyond the side pieces of the frame of the loom and notches 16 formed in the same will be located beneath the warp threads 6, 6. The rods 15 at one end are provided with slots 85 in which will lie the ends of the pins 13, such pins limiting the sliding movement of the rods as well as retaining the same in the slots in the brackets 9.

The construction of the brackets and the rods is such that the rods may be slid in their supports and upward movement of the slotted ends of the rods which are engaged by the pins 13 will be prevented. When it is desired to place needles upon the rod 15, the handles 11' on that end of the rod which engages with the bracket 9' is raised and the pin 13 that is carried by the block 11 of the bracket 9 serves as a fulcrum for the rod so that when the end of the rod is lifted out 110

of its bracket 9, it may be raised sufficiently to string the drops thereon.

When the fabric that is being woven is coarse, a single bar will suffice, but when the fabric is fine, I use two similar bars supported by a single bracket, and I am not limited to the exact position of the bars upon the loom, and it will be noted that when two bars or rods 15 are used, they will be maintained in parallel relation, one to the other, and separated from each other a distance equal to one-half the width of the needles 16.

The notched slideable bar or bars 15 are each provided on their upper edge with teeth 17 of appropriate configuration and a preferred form is to cut two slots 18, 18 which converge upward, and to remove a part of the upper surface of the bar which will leave a raised portion 16' between the slots or converging slots 18 with inclined end walls, as will more fully appear by reference to Fig. 4 of the drawings. The slots or recesses 18 are of a width which will only slightly exceed the thickness of the needles 16. The rods 15 in their preferred form are tapered in cross section, the thickest portion thereof being located farthest from the teeth, as will be seen by reference to Fig. 10 of the drawings, or the same object may be attained by constructing the bars so that they will be concave on both sides. The purpose of this construction of the bar 15 is to prevent the notches or teeth 17 engaging with the suspended drops when the bar is slid from left to right, as such engagement of the bar with the suspended drops would be objectionable and would be likely to mislead the operator in locating the break.

The needles or drops 16, as heretofore stated, are strung upon the rods 15 and these needles are made up from thin sheet metal, as steel or hard brass. The upper ends of the drops have therethrough an eye 19 and at a suitable point below the eye, there is an elongated opening 20. The eye 19 may be round or oval and the warp thread is passed through this eye. The width of the slot will exceed the width of the bar 15 so that the drops 16 may be easily strung thereon.

When the bars or notched rods are maintained at right angles with the warp threads the drops may have their upper portions, below the eye and above the slots, twisted or bent almost at right angles with the body portion of the drops, and if it is considered desirable to use a flat drop, the bar or bars 15 may be maintained to extend diagonally from one side of the frame to another, and this may be considered a preferred arrangement where there are a large number of warp threads as in weaving fine fabrics, but for heavier material, the rods may be at right angles to the warp, and the drops bent or twisted above the slot.

The slots at the ends of the bars 15, have a length sufficient to admit of a longitudinal movement of the bar of an inch and one-half which will give an opening that is sufficient not only to practically locate the broken warp and pick up the ends but re-thread the drop.

In operation, when a single rod 15 is used and a warp thread is broken, the drop will fall and may be readily seen in the dropping and it will either rest upon the higher portion of the twisted bar or between two such portions. By manually moving the rod from right to left, the drop will enter an inclined recess or slot which will incline the drop that has fallen so that it will shove the drops that are suspended by the warp along the bar without binding, until movement of the bar is arrested by the end of the slot contacting with the pin that intersects the slot. The drops when resting upon a bar and the bar being moved longitudinally will effect an inclination of the drop and thus provide a larger space through which to pick up the warp and unite the ends thereof. It will also be noted that the eye of the drop through which the warp is passed is at its upper end and above the slot through which the bar passes. When two notched rods or bars are used the drops when a thread breaks will fall and engage a notch in one of the bars, and when such bar is moved longitudinally the drop which overlaps the drop on an adjacent bar will engage the suspended drop and thus a fallen drop will not only be carried by the bar upon which it is strung but will also move the drops that are suspended and are strung upon the adjacent bar.

This break detector and warp separator is adapted for use with different types of looms, and may be used in conjunction with mechanical stop motions for power looms in which is used a normally stationary notched bar and a reciprocative notched bar that are locked together by the falling of a drop, so that one of the bars will actuate an appropriate stop motion.

I claim

1. In a warp thread detector for looms, vertically slotted brackets maintained by the frame of the loom; one of said brackets carrying laterally projecting pins, a bar provided with a slot through which the pin carried by the bracket is passed, said bar having recesses with oppositely inclined ends, and drops having eyes through their uppermost ends and slots below the eyes for the passage through the slots of the bars.

2. In a break detector and manually operated warp separator for looms, a slideable bar provided with notches which have at their ends open ended and upwardly converging recesses, drops mounted on the bar which are adapted to assume an inclined po

- sition when supported by the bar and when said bar is moved longitudinally.
3. In a warp thread detector for looms, vertically slotted brackets associated with a frame of a loom, one of the brackets being provided with a laterally projecting member, a detector bar provided at one end with a slot through which the member carried by the bracket is passed, said detector bar having recesses with oppositely inclined ends converging upwardly, and drops mounted upon the bar and held normally out of engagement with the recesses by the warp threads of the loom.
- 15 4. In a break detector for the warp threads of looms, brackets maintained by opposite side bars of the frame of the loom and positioned out of transverse alignment one with the other, parallel bars associated with the brackets to extend diagonally across the frame of the loom to be maintained at an angle with the warp threads and drops associated with the bars.
5. In a break detector and manually operated warp separator, parallel maintained slidable bars having drop engaging notches, the end walls of the notches converging upward to provide the bars with inclined drop engaging portions, warp maintained drops which are adapted when maintained solely by engagement by a bar and when moved with the bar to assume an inclined position with respect to the bar with which it engages.
6. A manually slidable or longitudinally movable warp detector bar for looms, having a notched portion with which drops may engage, the notches having a part located below the plane of the upper surface of the bar, and open ended downward diverging recesses which extend beyond the part of the notch that is located below the plane of the upper surface of the bar, and drops provided at their upper ends with eyes and below the eyes with slots for the passage of the detector bar.
7. In a warp thread detector for looms, a notched detector bar associated with a frame of the loom and provided with recesses; the bottom of the major portion of each recess being parallel to the edge of the detector bar, said recesses having end portions which are oppositely inclined to converge upwardly and extend below the bottom of the aforesaid major portion of the recesses, and drops of a thickness not exceeding the width of the deeper portions of the recesses which are adjacent to the inclined ends thereof.
- In witness whereof I have hereunto set my hand and seal this 17th day of July, 1913.
- WILLIAM OLDFIELD.
